UNITED STATES PATENT OFFICE.

WILLIAM GRIMLEY, OF SMETHWICK, ENGLAND.

PUMP OR SPRAYER FOR HORTICULTURAL PURPOSES.

Application filed November 11, 1927, Serial No. 232,694, and in Great Britain March 25, 1927.

This invention relates to pumps or sprayers of the kind comprising an outer chamber containing an inner pump cylinder having a reciprocating piston, the outer container being fitted with a valve chamber adjacent the inner end of the inner pump cylinder and the liquid being drawn into the pump cylinder through the valve chamber, and on the return stroke being pumped from the pump cylinder through a valve in the valve chamber to the outer chamber, from whence it is discharged. This kind of pump or sprayer has hitherto been used only as a hand sprayer, i. e., the apparatus has been relatively small and has been adapted to be held in the left hand while the piston rod has been reciprocated by the right hand, the sprayer being commonly used either in a substantially horizontal position or with its delivery end pointing upwards. The present invention has for its primary object to construct a pump having the features referred to but comprising certain improvements which permit the liquid being discharged at a greater pressure than hitherto and, further, which is so constructed that in use it is held in a vertical position by providing it with a foot piece whereby it may be steadied and is operated preferably by both hands.

In a pump working upon the principles which have been described, assuming that the pump is originally full of air this air is pumped into the outer chamber and compressed to a relatively high pressure so that the liquid which is subsequently pumped into the outer chamber is subject to this pressure.

One of the advantages obtained by my improved construction is that the compressed air is always retained in the outer chamber and is prevented from escaping therefrom owing mainly to the position in which the pump is always used.

One of the features of the present invention is to provide a delivery compartment at the lower end of the outer chamber, this compartment being formed by a transverse partition extending across the outer chamber, this partition carrying a tube which extends upwardly within the outer chamber and has an opening at or near its upper end while the delivery compartment is provided with a discharge passage or tube projecting laterally therefrom.

With this arrangement the liquid can enter the delivery compartment only by passing

through the tube carried by the partition, and above the end of this tube I prefer to provide a transverse baffle extending partly across the outer chamber.

The construction enables a local pressure to be generated in the delivery chamber which is higher than the average pressure in the outer chamber so that an improved discharge is obtained.

If required, the delivery compartment may be formed by means of a cap screwing on to the lower end of the outer chamber, the partition which has been referred to being held between a shoulder in this cap and the lower edge of the outer chamber.

A further feature of the present invention is to provide the lower end of the apparatus with a foot piece which may be in any convenient form and which may be provided with screw holes so that it can readily be screwed to a short length of wood upon which the operator can stand to hold the pump steady while pumping with both hands.

Referring to the drawings:

Figure 1 is a perspective view showing one form of my invention.

Figure 2 is a sectional view thereof.

Figure 3 is a section on line 3—3 of Figure 2.

In the construction illustrated the apparatus consists of an outer chamber 1 within which is fixed an inner pump cylinder 2 having a piston 3 and piston rod 4 which passes through a suitable stuffing box 5 and is provided with a transverse handle 6 suitable for operation by two hands.

The upper end of the outer chamber 1 is closed by a cap 7 having a small tube 8 protected by a cap 9, the arrangement being such that air can enter or pass out through the tube 8 but the entrance of dirt is prevented by the cap 9.

The annular space between the pump barrel 2 and the outer chamber 1 is closed by a flange or plate 10 so that the air which enters or leaves the tube 8 communicates only with the pump barrel 2 and not with the outer chamber 1.

The forward end of the pump barrel 2 is closed by a cap 11 and upon the exterior of the outer chamber 1 is a valve chamber 12 having a removable cap 13 containing a non-return valve 14.

Within the valve chamber is a cage 15 containing a second non-return valve 16.

Gratings or cross bars 31 are provided for retaining the valves 14 and 16 in their pockets from which they might otherwise fall out.

5 A tubular passage 17 extends from the forward end of the pump barrel 2 to the valve chamber 12.

At its lower end the outer chamber 1 is closed by a partition 18 which is held between a shoulder 19 on a cap 20 and the end of the 10 outer chamber 1.

At its centre the partition 18 is provided with a tube 21 which extends upwardly and has a transverse branch 22 which is open at the end.

15 Upon the top of the branch 22 is fixed a baffle plate 23 of part circular form as shown clearly in Figure 3, this baffle plate extending only partly across the outer chamber.

In the side of the cap 20 is a delivery tube 20 24 extending transversely and preferably in an upwardly inclined direction as shown.

The lower end of the cap 20 is provided with a spigot 25 which extends through a portion 26 of a stirrup like foot member 27, a 25 nut 28 securing the foot member or bracket to the cap 20.

The foot member or bracket 27 is provided with foot pieces 29 which have screw holes 30 by which they may be screwed to a short 30 piece of wood or other suitable material.

In operation, before starting the outer chamber 1 is full of air and upon the piston 3 being reciprocated liquid is drawn in past the valve 14 through the tube 17 into the 35 pump cylinder 2.

Upon the return stroke this liquid is forced again through the tube 17 and into the valve chamber 12, from whence it passes past the valve 16 into the outer chamber 1. No delivery takes place through the tube 24, however, until there is sufficient liquid in the outer 40 chamber 1 to reach the open end of the tube 22.

The pumping of liquid into the outer chamber 1 causes the air which was there originally to be compressed. This compressed air becomes imprisoned at the upper part of the outer chamber 1 and since the pump is always used in the position shown in the drawing, this air never escapes from the outer 50 chamber.

With the apparatus shown it is possible to generate a very considerable pressure so that if pumping ceases, delivery of the liquid from 55 the passage 24 will continue for a considerable time until the air contained in the outer chamber 1 has lost its pressure.

What I claim then is:—

1. A pump having in combination an outer 60 casing forming a pressure chamber, a pump barrel within said casing, a reciprocal piston and piston rod within said barrel, valve controlled means controlling the passage of liquid to said barrel from an external source of

supply and the passage of said liquid from 65 the barrel to said pressure chamber, a cap mounted on one end of said outer casing, a partition within said chamber and disposed between said cap and the adjacent end of said outer casing and at a distance from the former 70 whereby a delivery chamber is formed within said chamber and cap, and said delivery chamber having inlet and discharge openings for the liquid.

2. A pump having in combination an outer 75 casing forming a pressure chamber, a pump barrel within said casing, a reciprocal piston and piston rod within said barrel, valve controlled means controlling the passage of liquid to said barrel from an external source of 80 supply and the passage of said liquid from the barrel to said pressure chamber, a cap mounted on one end of said outer casing, a screw threaded spigot integral with said cap and projecting therefrom, a stirrup like foot 85 piece having a short hollow boss through which said spigot is adapted to pass, and a nut adapted to screw onto said spigot and clamp the said boss between the said cap and itself.

3. A pump having in combination an outer 90 casing forming a pressure chamber, a pump barrel within said casing, an annular plate having a flange adapted to fit over one end of said outer casing and another flange of smaller diameter adapted to be fitted on to one end of said pump barrel and said plate being adapted to close the adjacent end of the said pressure chamber, a further screw threaded flange on said annular plate, an internally 100 screwed cap adapted to screw on to said screwed flange, a reciprocal piston and piston rod within said barrel, said piston rod being adapted to pass through said internally 105 screwed cap, valve controlled means controlling the passage of liquid to said barrel from an external source of supply and the passage 110 of said liquid from the barrel to said pressure chamber, a cap mounted on one end of said outer casing, a partition within said chamber and disposed between said cap and the adjacent end of said outer casing and at a distance from the former whereby a delivery chamber is formed within said chamber and cap, said delivery chamber having inlet and 115 discharge openings for the liquid, a screw threaded spigot integral with said cap and projecting therefrom, a stirrup like foot piece having a short hollow boss through which said spigot is adapted to pass, a nut adapted to screw onto said spigot and clamp the said boss between the said cap and itself, and said 120 foot piece having projecting portions provided with screw holes whereby it may be secured to a support.

In witness whereof I affix my signature.

WILLIAM GRIMLEY.
